[57] CLAIM

The ornamental design for a telephone set, substantially as shown.

DESCRIPTION

FIG. 1 is a top plan view of a telephone set showing my new design;

FIG. 2 is a bottom plan view thereof;

FIG. 3 is a top plan view of the stand and a right side elevational view of the handset spaced apart;

FIG. 4 is a rear elevational view thereof;

FIG. 5 is a right side elevational view of the stand and a bottom plan view of the handset spaced apart; and

FIG. 6 is a front elevational view of the stand of the set and a front elevational view of the handset spaced apart. The cord is shown in fragmentary form for ease of illustration.
